BUCKLE

William Gency, New Britain, Conn., assignor to
 North and Judd Manufacturing Company, New
 Britain, Conn., a corporation of Connecticut

Application November 13, 1937, Serial No. 174,382

4 Claims. (Cl. 24—230)

This invention relates to buckles for wearing apparel such as belts.

An object of the present invention is to provide an improved buckle of the type wherein one part telescopes into the other and engages same in interlocking position.

A further object is a buckle which is simple in construction and effective in operation and so manufactured that upon slipping one part within the other they will interlock and remain interlocked until manually released.

Other objects will be in part obvious and in part pointed out more in detail hereinafter.

The invention accordingly consists in the features of construction, combination of elements, and arrangement of parts which will be exemplified in the construction hereafter set forth and the scope of the application of which will be indicated in the appended claims.

In the accompanying drawing wherein is illustrated one embodiment which the present invention may take:

Figure 1 is a front view of the buckle as applied to the end of a belt;

Fig. 2 is a rear view of the assembled buckle in locked position;

Fig. 3 is a rear view of the front member of the buckle;

Fig. 4 is a rear view of the rear member of the buckle;

Fig. 5 is a sectional view on the line 5—5 of Fig. 2;

Fig. 6 is a plan view partially broken away to show the parts in interlocking engagement;

Fig. 7 is a view similar to Fig. 6 showing the relative position of the parts as they are moved into interlocking engagement; and

Fig. 8 is a view similar to Fig. 7 with the rear plate moved further towards interlocking engagement.

Referring to the drawing, there is provided a front plate A and a rear plate B; the rear plate being adapted to telescope within plate A and be detachably connected thereto. These plates may be of any desired shape and configuration and are preferably formed from stampings of sheet metal having an inherent resiliency. Each plate is provided at its trailing edge with a suitable clamping member C adapted to secure each member to one end of a belt D. The foregoing plates are all of usual construction and are common to buckles of this type.

In accordance with the present invention, the front plate A is preferably longitudinally curved and has rearwardly turned flanges 11 at its upper

and lower edges which are substantially coextensive with the width of the plate A. Turned inwardly from flanges 11 and parallel to plate A are a pair of oppositely disposed flanges or guide members 12 which are spaced from plate A to serve as a guide therewith. The guide members 12 are relatively narrow, and the trailing edges 13 of each further serve as a locking shoulder.

The rear plate B is stamped from one piece and is of such size that its top and bottom marginal edges are receivable within the guideway formed by flanges 11, member 12 and the rear face of the front plate A. Plate B has cut therein oppositely disposed symmetrical slots 14 which extend from the top and bottom marginal edges at a point left of the vertical center angularly toward the trailing edge and terminate at spaced points to the right of the center, thus dividing the plate into a body part 15 and a spring member 16 extending outwardly from the body part 15 and interconnected thereto by the throat or biasing connection 17 intermediate of the ends of the slots. The body part 15 includes the two outwardly extending fingers 18, the leading edges of which are rounded to form positioning shoulders 19. The spring member 16 has its marginal edges rearwardly turned to form locking lips 20 having cammed rear faces 21 and locking shoulders 22. Inasmuch as the trailing edge of the spring member 16 is symmetrical to the leading edge of the body portion 15, the locking lips are adjacent the leading edge of the outwardly extending fingers 18 of the body part with the positioning shoulders 19 intermediate of the locking lips 20 and the throat or biasing connection 17, and the throat 17 intermediate of shoulders 19 and the trailing edge of plate B. Plate B is further distorted to angularly space the spring member 16 in a plane rearwardly of the plane of the body part 15, thus angularly spacing the locking lips 20 from the positioning shoulders 19, but it is apparent that if spring 16 and locking lips 20 are biased rearwardly the locking lips will be in substantial alignment with the shoulders (see Fig. 8).

With the arrangement described, it will be noted that the spacing between the front face 23 of flanges 12 and the rear face of plate A is less than the angular spacing between the cam faces 21 of the locking lips 20 and the positioning shoulders 19, and also that the flange 12 is of greater width than the distance between the trailing edge or locking shoulder 22 of the locking lips 20 and the trailing edge of the guide member 13. Thus, when plate B is inserted into plate

A, the cam face 21 of locking lips 20 will be received on the front face 23 of guide members 12 whereupon the plate B may be moved until positioning shoulder 19 abuts the rear face of plate A (see Fig. 7). Upon moving the rear plate further towards locking engagement, the spring 16 will be biased or pivoted on the throat 17 to cause the locking lips to be moved forwardly into substantial alignment with the positioning shoulders 19 and when moved a predetermined distance greater than the width of guide 12 the spring 16, because of the inherent resiliency of the metal, will assume its normal position relative to body part 15 and position the locking shoulders 22 in engagement with the trailing edges 13 of the guide member 12 and retain the plates in interlocked engagement. With the parts so positioned, in order to release same it is necessary to press forwardly on the spring member 16, thus pivoting it to lift the locking lips 20 out of engagement with the trailing edges 13. With the locking lips thus moved into substantial alignment with the positioning shoulders 19, plate B may be slipped out of engagement with plate A.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

It is also to be understood that the language used in the following claims is intended to cover all of the generic and specific features of the invention herein described and all statements of the scope of the invention which, as a matter of language, might be said to fall therebetween.

I claim as my invention:

1. A buckle of the character described, comprising two separable plates, one of said plates being provided with oppositely disposed guide members spaced rearwardly from and parallel thereto, the other plate being receivable between said guide members and said first plate, said second plate having a body portion and a spring member extending outwardly and angularly spaced from the body portion and resiliently connected thereto, rearwardly turned locking lips provided on the marginal edges of said spring member and engageable behind the trailing edge of said guide members, the angular spacing of said locking lips from said body portion of said second plate being greater than the spacing between said first plate and the guide members of said first plate, whereby when said locking lips are inserted behind said guide member said spring will be biased into substantial alignment with the body portion to permit said plates to be moved into interlocking engagement.

2. A buckle of the character described, comprising two separable plates, one of said plates being provided with oppositely disposed guide

members spaced rearwardly from and parallel thereto, the other plate being receivable between said guide members and said first plate, said second plate having a body portion and a spring member extending outwardly and spaced angularly from the body portion and resiliently connected thereto, said spring member having at its marginal edges rearwardly turned locking lips engageable behind the trailing edges of said guide members, said locking lips being adapted to be positioned on the front face of said guide member when the body portion abuts the rear face of said first plate, whereby said spring will be biased into substantial alignment with the body portion to permit said second plate to be moved into interlocking engagement with said first plate.

3. A buckle of the character described, comprising two separable plates, one of said plates being provided with oppositely disposed guide members spaced rearwardly from and parallel thereto and provided with a trailing edge, the other plate being receivable between said guide members and said first plate, said second plate having a body portion, a spring member extending outwardly from the body portion and resiliently connected thereto, said spring member having at its marginal edges rearwardly turned locking lips engageable behind the trailing edge of said guide members, positioning shoulders carried by said body portion intermediate of said locking lips and resilient connection, said locking lips being positioned rearwardly of the plane of said shoulders and adapted when inserted behind said guide means to be biased into alignment with said shoulders whereby said second plate may be moved into interlocking engagement with said first plate.

4. A buckle of the character described, comprising two separable plates, one of said plates being provided with oppositely disposed guide members spaced rearwardly from and parallel thereto, the other plate being receivable between said guide members and said first plate, said second plate having a body portion, a spring member extending outwardly from the body portion and resiliently connected thereto, said spring member having at its marginal edges rearwardly turned locking lips provided with cammed faces and adapted to be engaged behind the trailing edge of said guide members, positioning shoulders carried by said body portion intermediate of said locking lips and resilient connection, said locking lips being angularly spaced from said shoulders whereby when said cam surfaces are received on the front face of said guide members said shoulders abut the rear face of said first plate where upon further movement of said second plate said locking lips will be biased into substantial alignment with said shoulders to permit said second plate to be moved into interlocking engagement with said first plate.

WILLIAM GENCY.
